UNITED STATES PATENT OFFICE.

WILLIAM H. WOOD AND GEORGE RICHMOND, OF BROOKLYN, NEW YORK.

CONDENSE-WATER COOLER FOR REFRIGERATING AND ICE MACHINES.

SPECIFICATION forming part of Letters Patent No. 268,349, dated November 28, 1882.

Application filed September 4, 1882. (No model.)

To all whom it may concern:

Be it known that we, WILLIAM H. WOOD and GEORGE RICHMOND, of Brooklyn, in the county of Kings and State of New York, have invented certain new and useful Improvements in Condense-Water Coolers for Refrigerating and Ice Machines; and we do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical section of the apparatus; and Fig. 2 is a sectional view of the same laid through the horizontal plane indicated by the broken line *xx* in Fig. 1.

Similar letters of reference indicate corresponding parts in both the figures.

Our invention contemplates the construction of an apparatus designed to cool the condense-water used in the condenser or condensing apparatus of refrigerating-machines, or machines for manufacturing ice, in cases where a flow of cold water is not readily obtainable; and it consists in the construction and arrangement of parts of the same, as hereinafter more fully described and claimed.

Our apparatus consists of a tank, A, of the requisite capacity, and by preference of square or rectangular shape. Upon this tank is superimposed a smaller tank, (shown at B,) formed by raising the sides of the main tank above the roof thereof. The interior of tank A is divided by a series of vertical transverse walls or partitions (shown at *a*) into a series of chambers or compartments, (shown at C C' C² C³ C⁴), which communicate with one another through openings *c*. At one end of the tank is an inlet, J, and at the other end is the outlet L, which may lead into a suction fan or blower, (shown at K.) Every alternate compartment (represented in this case by the compartments C' and C³) is foraminated at the top, as shown at *b*, so that water placed in the upper tank, B, will fall into the respective compartments in the form of a fine shower. A suitably-constructed pump, D, is employed for feeding the water contained in the lower part of the tank A through a pipe, F, into the upper tank, B, into which it is discharged, as shown in Fig.

1; and a force-pump, E, which may either be independent of the pump D or form part of the same, as in Fig. 2, forces water (preferably at a pressure of about seventy pounds to the 55 square inch) through the pipe F' into a series of horizontal pipes, (shown at G,) which enter the compartments C² and C⁴ through the side of the tank. Each of these pipes G has a series of spraying-nozzles, H, the several pipes 60 being closed at their inner ends, so that the water forced into them will escape through the nozzles in the form of very fine spray, the nozzles being provided with spraying-disks, consisting essentially of two holes drilled at right 65 angles, so that the escaping jets will impinge upon and atomize each other.

From the foregoing description, taken in connection with the drawings, the operation of this apparatus will readily be understood. 70 Dry or unsaturated air enters the compartment C⁴ through the inlet J, and passes through the apparatus, through its several compartments, as indicated by the arrows, finally escaping at the opposite end of the apparatus 75 through the aperture L. In its passage through the apparatus it intermingles with the fine spray, which in compartments C² and C⁴ in the form of mist, and in compartments C' and C³ in the form of a finely-subdivided shower, 80 permeates said compartments, becoming saturated air as it passes through, and effectually cooling the water by absorbing its heat. In the application of the apparatus to our improved refrigerating and ice machine, which 85 forms the subject of a separate application for Letters Patent of even date with this present application, the water on its way from the bottom of tank A to the upper tank, B, is circulated through the feed-water pipe H, (shown 90 in the said application,) through the condensers D, and finally discharged through the outlet J (shown on Figs. 1 and 2 of the said application) into the upper tank, B.

It is desirable that the lower tank, A, should 95 be of large dimensions, or of a capacity to contain always a large surplus of water, to provide for the loss by evaporation and absorption by the air.

We do not limit ourselves to any particular 100 means or mechanism for feeding the dry air through the apparatus, as many different de-

vices may be employed for that purpose. The air may either be forced or blown through the apparatus, or it may be drawn through it by suction; or the apparatus may be used in connection with a flue, chimney, or ventilating shaft, as well as with a fan or blower.

It is also obvious that our apparatus may be used with advantage for cooling water or other liquids generally without reference to the purpose to which these are to be put; and we desire it, therefore, understood that we do not limit or confine the use of this apparatus to our improved refrigerating and ice machine.

Having thus fully described our invention, we claim and desire to secure by Letters Patent of the United States—

1. The tank A, divided by the transverse partitions α into the compartments C C' C² C³ C⁴, communicating with one another, as shown, and provided with a superimposed tank, B, having its bottom foraminated at b, substantially as and for the purpose shown and set forth.

2. The tank A, divided into a set or series of vertical compartments communicating with one another, and every alternate compartment having a foraminated roof, substantially as and for the purpose shown and set forth.

3. The tank A, divided into a set or series of vertical compartments communicating with

one another, and every alternate compartment 30 having a series of spraying-pipes or atomizers, G H, substantially as and for the purpose shown and set forth.

4. The tank A, divided into a set or series of vertical compartments communicating with 35 one another, every alternate compartment having a foraminated roof, and the compartments between these having each a series of spraying-pipes or atomizers, G H, substantially as and for the purpose shown and set forth.

5. The combination of the tank A, having the air-inlet J and outlet L, and divided into compartments, as shown, spraying-pipes or atomizers G H, tank B, feed-pipes F and F', and pumps or mechanism suitably constructed 45 and arranged for feeding air through the apparatus, and water from the bottom of tank A into the upper tank, B, and into the atomizers G H, substantially as and for the purpose herein shown and specified.

In testimony that we claim the foregoing as our own we have hereunto affixed our signatures in presence of two witnesses.

WILLIAM H. WOOD.
GEORGE RICHMOND.
